UNITED STATES PATENT OFFICE.

EDWARD P. DICKEY, OF HARVEY, AND GEORGE H. IRWIN, OF CHICAGO, ILLINOIS.

TRACTION TREAD FOR WHEELS.

Application filed May 25, 1922. Serial No. 563,482.

To all whom it may concern:

Be it known that we, EDWARD P. DICKEY and GEORGE H. IRWIN, citizens of the United States, residing, respectively, at Harvey, in the county of Cook and State of Illinois, and at Chicago, in the county of Cook and State of Illinois, have jointly invented certain new and useful Improvements in Traction Treads for Wheels, of which the following is a specification.

This invention relates to traction wheels of that class in which the tread while sustaining the vertical load imposed through the wheel, will enter into non-slipping engagement with soft ground over which it travels by developing limited penetration of the ground; and particularly to wheel treads in which the penetration elements comprise substantially radial vanes extending laterally from a medial circumferential rib, and the load bearing surfaces between these vanes are afforded by webs which are concaved and inclined to the medial rib in a manner to render the cavities, defined by the rib, vanes, and webs, self clearing of the earth-cast formed therein.

One object of the invention is to provide a form of cavity defined by a rib, vanes, and a web, which will render the vanes more efficient in gearing the tread to the surface over which it travels, and render the cavities more efficient in clearing themselves of the earth-cast which is being continually formed therein; and to these ends, one feature of the invention consists in locating the concave or trough-like bottom of the cavity radially inward from the crests of the vanes and rib; causing the bottom of the cavity to merge into the rib through means of a substantially flat incline which forms the inner end of the cavity and exercises a strong lateral displacing influence upon the earth-cast; and causing the sides of the concavity to merge with the vanes at a substantial distance radially inward from the penetrating edges of the vanes so that the latter stand out as clear and unobstructed resisting surfaces.

Another object of the invention is to adapt a tread of the class and type described, namely, a web composed of a medial circumferential rib, radial vanes, and load-supporting webs, to be made in sections and applied to the felly of a wheel to render the latter suitable for traction purposes; also

to develop a sectional wheel tread of the class described, which will be very light in proportion to its strength; to provide a construction of tread segments which will facilitate application to the rim of the wheel and will become mutually self sustaining in the circumferential direction when applied. Accordingly, another feature of the invention consists in subdividing a traction tread of the class described in radial planes bisecting vanes of the wheel at their penetrating edges; the opposed faces of the vanes resulting from the subdivision being preferably diverged in a manner to limit contact to the outer portions thereof; and the resultant segments, preferably including one or more vanes intermediate of the bisected vanes which constitute the ends of the segment, being fashioned to enter into bearing upon the wheel at the base of each vane in order to sustain the vertical load of the wheel.

Another object of the invention is to provide a design of rim segment which, while meeting the several conditions above described, including lightness of construction, will be adapted for production economically and durably by the process of casting or forging.

In order that the invention may be fully understood, the preferred embodiment thereof will now be described in detail, reference being had to the accompanying drawings, in which—

Figure 1 is a side elevation of a standard construction of tractor wheel having applied thereto a tread embodying the several features of the present invention.

Figure 2 is a plan view of the same.

Figure 3 shows a portion of the rim and tread of Figure 1 on an enlarged scale.

Figure 4 is a section on the line 4x—4x of Figure 3.

Figure 5 is a section on the line 5x—5x of Figure 3; and

Figure 6 is a section on the line 6x—6x of Figures 4 and 5.

1 represents a circumferential medial rib lying in a radial plane transverse to the axis of the wheel, 2 and 3 represent two types of radial vanes extending transversely from opposite sides of the rib 1 and constituting penetrating elements of the wheel; and 4 represents webs filling the spaces between the vanes 2 and 3 and providing load

bearing areas to sustain the load imposed through the wheel while permitting predetermined penetration of the vanes.

As shown more clearly in Figures 4 and 5, 5 the webs 4 extend from the points 5 near the crest of the rib 1 laterally and radially inward to the side 6 of the tread, so that they develop outward displacement of the earth-cast that tends to form between the 10 vanes 2, 3, and they meet said vanes on the lines 7 which diverge inwardly from the penetrating edges of the vanes so as to leave progressively increasing free radial 15 engaging faces upon the sides of the vanes. 20 Webs 4 are concaved between the vanes 2, 3, so as to compact the earth-cast toward the center and away from the side walls of the vanes, but this concavity decreases and becomes an approximately flat incline as 25 20 the web merges with the rib 1, as shown more clearly at 5 in Figure 2. These features of the invention are obviously applicable to a tread which is formed integrally with the rim of the wheel, as well 25 as to a tread formed separately therefrom, or a tread made in sections and applied to the wheel.

Preferably, the tread is made separately 30 from the wheel and is hollowed out on the under side to as full an extent as possible, consistent with strength required. Accordingly, as shown more clearly in Figures 4 and 5, the transverse section of the rim presents an arched construction with convex under surfaces 8 corresponding substantially to the concaved surfaces of the webs, the arch finding its support upon the rim 9 at the points 10 beneath the outer margins of the webs, also through means of 40 feet 11 at the bases of the vanes 2, and preferably also through means of the fins 12 extending circumferentially across the lateral margins of the webs 4 and beneath the intermediate vane 3 in a manner to afford vertical support for the latter. The 45 transverse arch of the tread is strengthened by the vanes 2 and 3, which intersect the arch as shown in Figures 4 and 5, and develop a chord 13 on the under side of the 50 crest thereof in addition to the vanes which are on the outside and which constitute strong trussing members extending between the feet 11 on opposite sides of the tread, in the case of the vanes 2, or between a 55 pair of fins 12 on opposite sides of the tread, in the case of the intermediate vanes 3.

In order to secure the separately formed tread to the rim 9 of the wheel, bolts 14 are introduced through the supporting feet 11 60 and through the rim.

The separately formed tread is preferably constructed from a plurality of identical segments arranged in circumferential series upon the wheel, and these segments are subdivided in radial planes or vanes 2, and in

such manner that member 2^a of said vanes, which constitute the opposed ends of meeting sections, will assemble as complementary members to produce the complete vane. The opposed faces of the members 2^a are 70 formed at angles to the radial plane of subdivision between the sections so that sections meet only in the rib 1 and in the penetrating ends of the vane members. This enables the segments to sustain one another 75 in circumferential series and greatly simplifies the work of assembly; moreover, it leaves a segment substantially wedge-shaped in the radial direction so that the last section to be applied can be crowded in between adjoining sections, and when drawn to its seat, will properly distribute the sections, circumferentially, in the series.

The medial circumferential rib 1 is preferably developed with sufficient width to 80 constitute a smooth continuous tread for sustaining the load of the wheel on hard surfaces, the penetrating edges of the vanes 2 and 3 being sufficiently within the continuous tread in a radial direction to avoid injury to the road surface.

We claim:

1. A traction tread for wheels, comprising a medial circumferential rib having an axial dimension sufficient to constitute a smooth 95 load bearing tread, radial penetrating vanes projecting laterally from said rib and having their penetrating edges in a circumferential plane radially within the plane of said smooth tread, and load bearing webs 100 intermediate of said vanes, inclined laterally and radially inward from near the smooth tread, and meeting the side walls of the vanes on lines diverging radially inward from the penetrating edges of the vanes. 105

2. A traction tread formed separately from and constructed for attachment to wheels; said tread comprising a medial circumferential rib, radial penetrating vanes projecting laterally from said rib, and load bearing webs intermediate of said vanes; certain of said vanes having bearing feet through which they are stepped upon the wheel.

3. A traction tread formed separately 115 from and constructed for attachment to wheels; said tread comprising a medial circumferential rib, radial penetrating vanes projecting laterally from said rib, and load bearing webs intermediate of said vanes; certain of said vanes having bearing feet through which they are stepped upon the wheel; and circumferentially extending fins being provided at the margins of said webs 120 through which they bear upon the wheel.

4. A traction tread formed separately from and constructed for attachment to wheels; said tread comprising a medial circumferential rib, radial penetrating vanes projecting laterally from said rib, and load 125 bearing webs intermediate of said vanes;

- bearing webs intermediate of said vanes; certain of said vanes having bearing feet through which they are stepped upon the wheel; and circumferentially extending fins being provided at the margins of said webs through which they bear upon the wheel; said fins extending from one web to another, across the end of an intermediate vane, and affording vertical support for the latter.
5. A traction tread, comprising a medial circumferentially extending rib, vanes extending laterally therefrom, and webs filling the spaces between the vanes and extending from near the crest of the rib laterally and radially inclined to the sides of the tread; said tread being formed separately from and constructed for attachment to a wheel.
10. 5. A traction tread, comprising a medial circumferentially extending rib, vanes extending laterally therefrom, and webs filling the spaces between the vanes and extending from near the crest of the rib laterally and radially inclined to the sides of the tread; said tread being formed separately from and constructed for attachment to a wheel.
15. 6. A traction tread, comprising a medial circumferentially extending rib, vanes extending laterally therefrom, and webs filling the spaces between the vanes and extending from near the crest of the rib laterally and radially inclined to the sides of the tread; said tread being formed separately from and constructed for attachment to a wheel, and being subdivided into a circumferentially arranged series of sections.
20. 7. A traction tread, comprising a medial circumferentially extending rib, vanes extending laterally therefrom, and webs filling the spaces between the vanes and extending from near the crest of the rib laterally and radially inclined to the sides of the tread; said tread being formed separately from and constructed for attachment to a wheel, and being subdivided into a circumferentially arranged series of sections, the planes of separation being coincident with penetrating edges of some of the vanes.
25. 8. A traction tread, comprising a medial circumferentially extending rib, vanes extending laterally therefrom, and webs filling the spaces between the vanes and extending from near the crest of the rib laterally and radially inclined to the sides of the tread; said tread being formed separately from and constructed for attachment to a wheel, and being subdivided into a circumferentially arranged series of sections, the planes of separation being coincident with pen-
- trating edges of some of the vanes, and said sections being arranged to abut at said edges.
9. A traction tread for wheels, comprising a medial circumferential rib, radial 55 vanes extending laterally from said rib, and load bearing webs between said vanes, said tread being subdivided on radial planes extending through some of the vanes, and the vane members thus produced being provided with bearing feet adapted to support the tread sections upon the wheel.
10. A traction tread for wheels, arched in radial axial planes and providing by the crest of the arch a medial circumferential 60 tread surface having transverse vanes intersecting and strengthening the arch and providing penetrating elements for the tread.
11. A traction tread for wheels, arched 70 in radial axial planes and providing by the crest of the arch a medial circumferential tread surface having transverse vanes intersecting and strengthening the arch and providing penetrating elements for the tread; 75 said tread being formed separately from the wheel and having bearing feet adjacent its vanes.
12. A traction tread for wheels arched in axial radial planes to provide a medial 80 circumferential tread, and having the transverse vanes intersecting the arch forming penetrating members on the exterior of the tread and arch chords on the interior thereof.
13. In a traction tread for wheels, a medial circumferential rib, concavo-convex load bearing webs inclined laterally and radially inward from said rib, transverse vanes constituting penetration members on either side of said rib and sustaining the 85 rib from the wheel upon which the tread is mounted, and fins with the lateral margins of said webs sustaining the latter upon the wheel.
- Signed at Chicago, Illinois, this 28th day of April, 1922.
